UNITED STATES PATENT OFFICE

125,684

DESIGN FOR AN ELECTRIC TOASTER

Irving Edelman, Brooklyn, N. Y.

Application February 10, 1940, Serial No. 90,181

Term of patent 3½ years

To all whom it may concern:

Be it known that I, Irving Edelman, a citizen of the United States of America and resident of the Borough of Brooklyn, county of Kings, city and State of New York, have invented a new, original, and ornamental Design for Electric Toasters, of which the following is a specification, reference being had to the accompanying drawing, forming a part thereof.

In the drawing:

Figure 1 is a view in perspective of an electric toaster, showing my new design. The side oppo-

site the ornamental side shown is similarly ornamented.

Figure 2 is a top plan view of the same, on a slightly reduced scale.

Figure 3 is a view in elevation, also on a slightly reduced scale, of the end of the electric toaster concealed from view in Figure 1.

I claim:

The ornamental design for an electric toaster, as shown and described.

IRVING EDELMAN.
